Primary Examiner — Robert M Spear*Assistant Examiner* — Marissa Cash(74) *Attorney, Agent, or Firm* — Reinhart Boerner Van Deuren s.c.(57) **CLAIM**

We claim the ornamental design for a closure, as shown and described.

DESCRIPTION

FIG. 1 is a top perspective view of an embodiment of the claimed design;

FIG. 2 is a front view of the claimed design of FIG. 1, the rear view, the left side view and the right side view being the same as the front view;

FIG. 3 is a top plan view of the claimed design of FIG. 1; and, FIG. 4 is a bottom plan view of the claimed design of FIG. 1. The ornamental design which is claimed is shown in solid lines in the drawings. The broken lines in the drawings are for illustrative purposes only and form no part of the claimed design.

1 Claim, 4 Drawing Sheets(56)
